United States Patent Office.

MELVIN J. GASKILL, WILLIAM YOST, AND JOHN FERRIS, OF PLEASANT PLAIN, OHIO.

Letters Patent No. 98,051, dated December 21, 1869.

IMPROVED RAILWAY-SWITCH.

The Schedule referred to in these Letters Patent and making part of the same.

To all whom it may concern:

Be it known that we, MELVIN J. GASKILL, WILLIAM YOST, and JOHN FERRIS, of Pleasant Plain, in the county of Warren, and State of Ohio, have invented a new and improved Method of Adjusting Railway-Switches; and we hereby declare the following to be a full and exact description thereof, reference being had to the annexed drawings, forming part of this specification.

The nature of our invention consists in a cheap and easy mode of shifting the switches in railroads by the motion of the cars.

To enable others skilled in the business to make and use our invention, we will describe its construction and our method of using it.

Figures 1 and 2 represent a strong iron box or frame, A, containing two adjustable iron lugs, B B, a cross-beam, C, (fig. 2,) connecting the lugs, a transverse shaft, D, supporting the beam in the box, and having an arm, E, fastened on the opposite end of the shaft outside the box, a perpendicular shaft, F, with a screwthread, G, near the lower end, connecting with the arm E, and a hand-wheel, H, at the top, by which the lugs are operated, with an index, I, on its upper side.

Figure 3 represents a railroad, with a switch in working order.

The levers O O are fastened down in their places, on pivots M, far enough from the switch in either direction to allow it to be shifted before any weight from the moving train presses upon it.

These levers may be connected to the switch by any form of coupling, P P, that will communicate the motion of the lever to the switch.

The iron box A, with its adjustable lugs B, is made fast to any part of the cars or locomotive that may be desired, provided it is the proper height from the track, and is convenient for being worked effectually by a man on the moving train.

When the cars are in motion, if we wish to keep the main track, we keep the index I on the hand-wheel H, pointing directly forward.

The lugs B B will then be on a level, and will touch only the upper plane L, on the sides of the levers O, holding them straight in the centre of the track, and keeping the railway-switches in their proper places for the main road.

When it is desirable to turn off on right or left-hand tracks, we turn the hand-wheel H until the index points across the road to the right or left, as we wish to go.

One of the lugs will then drop down, so as to strike the lower plane K, in the lever O, and press it over while the other lug will be raised up to allow the upper plane, L, to pass under it.

The motion thus communicated to the levers by the lugs will be imparted to the switch, through the couplings P P and their connections, causing the switch to adjust itself to any other track we may select.

In practice it may be necessary to form a neutral position for the lugs under the cars, by having them more elevated than on locomotives, but the method of operating will be the same as described.

We do not claim the switch; but

What we do claim as our invention, and desire to secure by Letters Patent, is—

The combination of the lugs B, cross-beams C, shaft D, arm E, perpendicular shaft F, screw G, hand-wheel H, and index I, all constructed and operated as and for the purpose described.

MELVIN J. GASKILL.
WM. YOST.
JOHN FERRIS.
